ELECTRONIC TIMING AND CONTROL MEANS
FOR RELAYS

William A. Brown, Pensacola, Fla.

Application December 2, 1947, Serial No. 789,302

9 Claims. (Cl. 175—320)

1

This invention relates to an electronically controlled delayed action relay for closing an electrical circuit after a predetermined period of delay and thereafter opening said circuit after it has been energized for a predetermined period, and is particularly adapted for use in controlling the circuit through the actuating solenoid of a motion picture projector change-over switch, though by no means limited to such use.

In the showing of motion pictures it is usual practice to employ a plurality of projecting machines, one of said machines being in operation to show one reel of film while the other is loaded with the succeeding reel of film and maintained in readiness to be brought into operation at the exact instant that the showing of the film on the first projector is completed. Both of said machines are connected to a standard solenoid actuated change-over switch which has heretofore required to be manually actuated by the projectionist at the exact proper instant in order to result in a smooth change-over from one projector to the other.

In order to make such a change-over it has been necessary for the projectionist to watch the screen very carefully to detect visual change-over cues thereon, the first of these consisting of a warning or stand-by cue, which is followed after a predetermined interval by a change-over cue indicating the exact instant at which the change-over solenoid must be energized.

This has required that the projectionist devote his entire time and attention to making the change-over with resulting eye-strain, fatigue and nevertheless occasional unsatisfactory change-overs.

With the foregoing in mind, the present invention has for its primary object to provide a control device or relay which, though capable of other applications, is particularly adapted for controlling the energizing of the solenoid circuit in such a change-over switch, requiring manual actuation only to initiate its operation at the time of the visual warning or stand-by cue.

A further object is to provide such a device which may be set to effect an interruption of the controlled solenoid or other circuit a predetermined interval after same has been energized.

A further object is to provide such a device employing adjustable relay control means for varying the period of delay prior to energization of the controlled circuit and for also varying the period during which same remains energized.

A still further object is to provide signaling 55

2

or indicating means for informing the operator as to the initiation and duration of the controlling operation.

In the present application I have shown and described only the preferred embodiment of my invention, simply by way of illustration of the practice thereof as by law required. However, I recognize that the invention is capable of other and different embodiments and that the details thereof may be altered in various ways, all without departing from my said invention. Accordingly the drawings and description herein are to be considered as merely illustrative of the invention, and not as exclusive of other possible embodiments.

In the accompanying drawings, the figure represents a wiring diagram of apparatus embodying the invention.

Referring now in detail to the accompanying drawings, the embodiment of the invention shown therein by way of illustration comprises a suitable source of alternating current, such as a transformer having a primary coil 1 and secondary coils 2, 3 and 3' respectively.

25 A pair of thermionic rectifiers 5 and 5' respectively, preferably of the full wave type, serve as the timing and controlling elements of the invention, and each has its plate circuit and its filament circuit receiving current from said transformer.

30 By reference to the drawing, it will be seen that the plate circuit of rectifier 5 comprises the lines 6 and 7 respectively connecting the plates 8—8' thereof to opposite ends of the secondary coil 2; and in the plate circuit of rectifier 5' the plates 8'—8' are similarly respectively connected to opposite ends of the secondary coil 2, as by lines 6' and 7' respectively connected to said lines 6 and 7.

35 The filament circuit of rectifier 5 includes the lines 9 and 10 connecting the filament 11 in series with the secondary coil 3 to receive alternating current therefrom, and any suitable preferably adjustable current regulating device or means such as the potentiometer 12 interposed in said circuit to control the filament voltage and consequently the time required to heat the filament 11 to operating temperature. Preferably the arm or wiper 13 of the potentiometer 12 will have associated therewith a gauge or scale 14 which is calibrated to indicate the time that will be required to heat the filament 11 to operating temperature at different settings of the wiper 14, the wiper serving as an index with relation to the calibrations on said scale.

Rectifier 5' has a filament circuit similar to that of rectifier 5, same including the lines 9' and 10' connecting the filament in series with the secondary coil 3', a potentiometer 12' interposed in said circuit for the purpose aforementioned in connection with potentiometer 12, said potentiometer 12' preferably also having a scale 14' similar to scale 14 and for a similar purpose, though preferably the potentiometer 12' is adjustable to interpose a greater resistance in its respective filament circuit than is the potentiometer 12.

The rectifier 5 controls the closing of a normally open main or control relay, designated 15 in its entirety, which has its winding 16 normally 15 connected to the filament circuit of rectifier 5, as by the line 17, and to the plate circuit of said rectifier through the center of secondary coil 2 by means of a line 18; thereby establishing a direct current relay energizing circuit through the rectifier 5 and relay 15.

In order to eliminate alternating current from the relay winding 16, said energizing circuit may include a suitable filter consisting of a resistance 19 in series with the relay winding 16, and a capacitor or condenser 20 connected in parallel with said winding and said resistance.

Control relay 15 includes an armature 21 and its cooperating contact 22 both included in a circuit 30 which is controlled by said relay 15. Current may be supplied to said circuit 30 from any suitable source. Normally the armature 21 will be retained in open position out of engagement with the contact 22 by means such as a spring 23, but will be moved into engagement with said contact when actuated by energization of the winding 16. Said winding 16 is energized as soon as the rectifier filament 11 reaches operation temperature.

The rectifier 5' controls the opening of a normally closed cut-out relay 15' which has its armature 21' interposed at some suitable point to control the energizing circuit of control relay 15. Thus when winding 16' of the cut-out relay 15' is energized said armature 21' will move away from its contact 22' to de-energize the control relay 15, permitting the armature 21 thereof to be opened by spring 23 to interrupt the controlled circuit 30.

Such a cut-out relay 15' may be included in the direct current energizing circuit of its respective rectifier 5' in a manner similar to that of the control relay 15. Thus the winding 16' of relay 15' may be connected to the plate and filament circuits of the rectifier 5' by means of the lines 18 and 17' respectively. The energizing circuit of said relay 15' may include a filter circuit consisting of the capacitor or condenser 20', resistance 19', and winding 16' for the same purpose and arranged in similar manner to the corresponding elements of the relay 15. Suitable means such as the spring 23' normally retain the armature 21' in engagement with its contact 22'.

The potentiometer 12' of the cut-out relay 15' will be set to cause actuation of the said relay 15' a predetermined interval after the actuation of control relay 15.

In order that the flow of current through the filament circuits of both rectifiers 5 and 5' may be commenced at exactly the same instant, I provide a suitable means for simultaneously controlling both of said filament circuits. Such means preferably consists of any usual type of manual switch S disposed in the supply line of the primary coil 1 of the transformer.

To the end that the operator may have some means of readily ascertaining that the filament circuit of the rectifier 5 is energized and that the timing and/or rectifying functions thereof are proceeding properly, a visual signal in the form of a suitably colored incandescent lamp 25 may be connected across said filament circuit, as shown. Such a light 25 will be illuminated continuously from the time the switch S is closed, providing the filament circuit is in order.

In order to further inform the operator as to the length of time that the cut-in relay 15 is closed, I provide additional signal means preferably consisting of a suitable colored signal light 26 which is connected across the filament circuit of the rectifier 5' by means of a line 27.

Disposed in the line 27 is a switch arm 28 for cooperation with a contact 29 similarly disposed in said line 27. The switch arm 28 is coupled or ganged to the armature 21 of the relay 15 for simultaneous opening and closing therewith, so that, upon closing of the relay 15 and consequent energizing of the controlled device, the signal 26 will be actuated and will remain actuated until the cut-out relay 15' operates, at which time signal 26 will become immediately de-energized, thus indicating the opening of relay 15.

In practice the relay 15 may be of the double pole type, in which case the switch arm 28 may constitute one of the dual arms or armatures thereof.

In the operation of the invention the controlled circuit may have any desired electrical device or devices included therein. Where the invention is used for control of a projector change-over switch, as aforementioned, the actuating solenoid of such switch may be included in the controlled circuit 30.

With such arrangement, the projectionist will 40 adjust the potentiometer 12 so that the delay between the time the filament 11 is energized and the time it reaches operating temperature with resultant energization of the control relay 15, will be equal to the interval between the stand-by and 45 change-over visual cues shown on the screen.

At the same time the potentiometer 12' will be adjusted to cause a somewhat longer delay in the energization of its associated relay 15', the difference in the periods of delay caused by said potentiometers 12 and 12' obviously equalling the period during which the controlled circuit remains energized.

With the device thus arranged, the projectionist need watch the screen only long enough to detect 55 the first or stand-by visual cue, at which time he manually closes the switch S, simultaneously starting the motor of the incoming projector and initiating the operation of the device of the invention. At this time the indicator signal light 25 60 will flash on and will stay on as long as its respective filament circuit is energized.

Thereafter, the heating of the filament 11 and the consequent operation of the rectifier 5 will close the relay 15, with resultant closing of the 65 controlled circuit 30, thereby permitting energization of the solenoid or such other devices as may be included in said circuit.

Simultaneous with the closing of the relay 15, the signaling circuit 27 will be closed to energize 70 the signal 26 and thereby indicate such closing.

After relay 15 has been closed for a predetermined interval, preferably of sufficient duration to insure complete operation of the solenoid-actuated change-over switch, the subsequent coming into operation of the rectifier 5' and resultant 75

opening of the relay 21' will de-energize the relay 21, which will then return to open position, breaking the controlled circuit 30 and avoiding danger of injury to the solenoid in said circuit 30.

I claim:

1. Electronic timing and control means comprising a transformer, a switch disposed in the primary circuit of said transformer and controlling the energization thereof, a pair of thermionic full wave rectifiers each having a plate circuit and a filament circuit electrically connected to and receiving current from said transformer, current regulating means included in each said filament circuit, each said means being adjustable to delay the heating of its respective filament to operating temperature for various predetermined intervals following energization of said transformer, and a normally open control relay having an energizing circuit in series with one of said rectifiers to be energized by the rectified current therefrom, in combination with a normally closed cut-off relay having cooperating contacts disposed in the energizing circuit through said control relay, said cut-off relay having an energizing circuit connected to said other rectifier to be energized by the direct current therefrom and thus cause de-energization of said control relay after a given period of energization thereof.

2. Electronic timing means comprising a transformer, a pair of full wave thermionic rectifiers, each comprising a plate circuit and a filament circuit, both electrically connected to and receiving current from said transformer, adjustable current regulating means included in each said filament circuit to delay the actuation of its respective rectifier for a predetermined interval following the energization of said transformer, and a normally open cut-in relay in circuit with one of said rectifiers to be energized by the rectified current therefrom, in combination with a normally closed cut-off relay controlling the energizing circuit of said control relay, said cut-off relay being connected to said other rectifier tube to be energized by the rectified current therefrom, and thus cause de-energization of said control relay.

3. Electronic timing means comprising a transformer, a pair of full wave thermionic rectifiers, each comprising a plate circuit and a filament circuit, both of said circuits being electrically connected to and receiving current from said transformer, resistances included in said respective filament circuits to delay for predetermined intervals the heating of their respective filaments to operating temperature and the resultant actuation of their respective rectifiers, said resistances being of such relative values that the first of said rectifiers commences actuation a definite interval before the second thereof, and a normally open cut-in relay having an energizing circuit in series with said first rectifier to be energized by the rectified current therefrom, in combination with a normally closed cut-out relay having an energizing circuit in series with said other rectifier to be energized by the rectified current therefrom, said cut-out relay having cooperating contacts in the energizing circuit to said cut-in relay to de-energize same a predetermined time after its energization has commenced.

4. Electronic timing and control means comprising a source of alternating current, and a control switch in circuit therewith, a pair of thermionic full wave rectifiers, each comprising a plate circuit and a filament circuit, both of said circuits being electrically connected to and receiving current from said source, an adjustable

resistance included in each said filament circuit to delay the heating of its filament and the consequent actuation of its respective rectifier for a predetermined interval following the closing of said control switch, and a normally open control relay having an energizing circuit connected to one of said rectifiers to be energized by the rectified current therefrom, in combination with a normally closed cut-out relay having an energizing circuit connected to said other rectifier to be energized by the rectified current therefrom, said cut-out relay having circuit interrupting means disposed in and controlling the energizing circuit of said cut-in relay.

5. Electronic timing and control means comprising a source of alternating current, a pair of thermionic rectifiers, each having a plate circuit and a filament circuit electrically connected to and receiving current from said source, a common control switch in circuit with both of said filament circuits, means included in each of said filament circuits to delay the heating of the filament thereof for a predetermined interval following the closing of said switch, and a cut-in relay having an energizing circuit connected to one of said rectifiers to be energized by the rectified current therefrom, in combination with a cut-out relay comprising an energizing circuit connected to the other of said rectifiers to be energized by the rectified current therefrom, and circuit interrupting means energized by said energizing circuit of the cut-out relay, said means comprising actuating means and contacts controlled thereby, said contacts being disposed in the energizing circuit of the cut-in relay.

6. Electronic timing and control means comprising a source of alternating current, a pair of thermionic rectifiers, each having a plate circuit and a filament circuit electrically connected to and receiving current from said source, a common control switch in circuit with both of said filament circuits, means included in the filament circuit of the first of said rectifiers for retarding the actuation thereof relative to the second of said rectifiers, and a control relay in circuit with said second rectifier to be energized by the rectified current therefrom, in combination with a cut-out relay in circuit with said first rectifier to be energized by the rectified current therefrom, said cut-out relay being disposed to control the energizing circuit of said control relay.

7. Electronic timing and control means comprising a source of alternating current, a pair of thermionic rectifiers, each having a plate circuit and a filament circuit electrically connected to and receiving current from said source, a common control switch in circuit with both of said filament circuits, means included in the filament circuit of the first of said rectifiers for retarding the actuation thereof relative to the second of said rectifiers, and a control relay in circuit with said second rectifier to be energized by the rectified current therefrom, in combination with a cut-out relay in circuit with said first rectifier to be energized by the rectified current therefrom, said cut-out relay being disposed to control the energizing circuit of said control relay, a signaling circuit including a signaling device connected across the filament circuit of said first rectifier, and a switch disposed in said circuit for actuation by said control relay to close said circuit and energize said signaling device during the period when said control relay is energized.

8. Electronic timing and control means comprising a source of alternating current, a pair of

thermionic rectifiers, each having a plate circuit and a filament circuit electrically connected to and receiving current from said source, a common control switch in circuit with both of said filament circuits, means included in the filament circuit of the first of said rectifiers for retarding the actuation thereof relative to the second of said rectifiers, signaling means connected across the filament circuit of said second rectifier to indicate when same is energized, and a control relay in circuit with said second rectifier to be energized by the rectified current therefrom, in combination with a cut-out relay in circuit with said first rectifier to be energized by the rectified current therefrom, said cut-out relay being disposed to control the energizing circuit of said control relay, a signaling circuit including a signaling device connected across the filament circuit of said first rectifier, and a switch disposed in said circuit for actuation by said control relay to close said circuit and energize said signaling device during the period when said control relay is energized.

9. Electronic timing and control means comprising a source of alternating current, a pair of thermionic rectifiers, each having a plate circuit

and a filament circuit respectively electrically connected to and receiving current from said source, a common control switch in circuit with both of said filament circuits for simultaneously controlling same, means included in the filament circuit of the first of said rectifiers for retarding the actuation thereof relative to the second of said rectifiers, and a control relay having an energizing circuit connected to said second rectifier for energization by the rectified current therefrom, in combination with means actuated by the rectified current from said first rectifier for interrupting the energizing circuit through said control relay.
